UNITED STATES PATENT OFFICE.

AUGUST KADOW, OF TOLEDO, OHIO, ASSIGNOR TO THE VACUUM CASTING COMPANY, OF TOLEDO, OHIO, A CORPORATION OF OHIO.

VACUUM CONNECTION FOR MOLDS.

Application filed June 13, 1927. Serial No. 198,491.

This invention relates to a vacuum connection for a mold, and more particularly a connection for a mold section which is removably mounted upon a carrier.

5 The object of the invention is to provide a means by which an air tight connection between exhausting passages and the mold cavity can be made quickly and with the minimum opportunity for leakage.

10 Details of the invention will appear as the description proceeds.

In the accompanying drawings forming a part of this specification, Figure 1 is a side elevation of a portion of casting apparatus embodying the invention; Fig. 2 is a section approximately on the line 2—2 of Fig. 1.

15 In the embodiment of the invention disclosed in the drawings, a mold carrier 10 supports a mold section 11 by means of a detachable connection 12. A mating section 13 completes the mold, the mating section being supported in any desirable way.

20 A vacuum chamber 14 in the mold carrier is connected to an exhaust passage through a regulating valve 15. A control valve 16 governs the connection of the vacuum chamber 14 with the mold.

25 The casting cavity 17 in the mold is connected through a narrow slit with vacuum groove 18 in mold section 11. There are openings 19 through the wall of the mold into the vacuum groove, and stud pipes 20 are screwed into openings 19. Beneath control valve 16 there is a chamber 21 to which stud pipes 22 are connected. Lengths of flexible hose 23 connect stud pipes 20 and 22. A container 24 supports molten metal 25 in position to supply the mold with molten metal when air is exhausted from the mold cavity.

30 In the construction shown, a block 26 is provided in groove 18 and held therein removably by screws 27. The block does not completely fill the groove, but leaves a space 28 back of the block and a slit 29 above the block.

35 The mating mold section 13 is provided with a groove 30 in its face communicating with space 28 through slit 29. An extremely thin passage 31 between the mold sections connects the mold cavity with groove 30.

40 It will be readily understood that a certain degree of vacuum is maintained continuously within chamber 14. When the mold is to be filled its inlet is immersed in the molten metal and valve 16 is opened, whereupon the air moves from the mold cavity through

vacuum groove 18, openings 19, stud pipes 20, hose connections 23, stud pipes 22, chamber 21, and valve 16 to vacuum chamber 14.

45 In filling molds with metal, especially with metal which is fluid in the molten condition, the force with which the metal is moved into the mold must be carefully regulated. If the difference between the pressure on the metal and the pressure in the mold cavity is too great, there results spouting of the metal into the cavity with resultant openings in the casting. If the differential pressure is too little, the metal solidifies in the cavity before the cavity is completely filled, and thereby imperfect castings are produced. For this reason the degree of vacuum in the mold cavity must be accurately regulated.

50 It is desirable to have the mold sections readily removable from the carrier, as it is necessary to change the molds frequently for various reasons. In the construction of molds filled by the vacuum method, in glass making and similar operations where the vacuum method of filling the mold has been used largely, it has been customary to connect the mold cavity to the exhausting passages through the connections of the mold sections to the mold carrier. Where this is done, it is difficult to make air tight connections, and furthermore the leakage which is almost inevitable in the joints varies constantly from slight changes in the position of the mold section and because of varying temperatures. The result is that the degree of vacuum in the mold is affected by the leakage, and the effect of this leakage is constantly varying, so that it is impossible to regulate the vacuum within the mold as accurately as is desirable when casting fluid metals. By the connections disclosed in this application the likelihood of leakage is practically eliminated, and any leakage which does occur is substantially constant, so that the degree of vacuum within the mold can be accurately regulated.

55 The use of block 26 results in the distribution of the air along slit 20 when it is exhausted from groove 30, so that there is no material tendency for the metal to be drawn directly towards vacuum openings 19 more than toward other portions of the vacuum grooves. Block 26 is additionally advantageous because, in case of an imperfectly closing mold resulting in access of the liquid to the vacuum grooves, the block tends to prevent entrance of the metal to the exhaust passages.

Any small amount that may be drawn in through slit 29 solidifies in space 28, and removal of block 26 enables groove 18 to be quickly and easily cleaned. Comparatively serious difficulty would arise if the metal could be drawn directly into passages 20.

It will be readily understood that various changes can be made in the exact construction of the apparatus within the terms of the appended claims.

What I claim is:

1. A mold having therein a casting cavity and a vacuum chamber connected with said cavity through a narrow slit, a carrier for the mold, a detachable connection for the mold to the carrier, there being a vacuum chamber within the carrier and detachable vacuum connections between the vacuum chamber in the carrier and the vacuum chamber in the mold independent of the detachable mounting of the mold upon the carrier.
2. A mold having therein a casting cavity and a vacuum chamber connected with said cavity through a narrow slit, a carrier for the mold, a detachable connection for the

mold to the carrier, there being a vacuum chamber within the carrier and detachable pipe connections between the vacuum chamber in the carrier and the vacuum chamber in the mold independent of the detachable mounting of the mold upon the carrier, said connections comprising a stud pipe leading from the vacuum chamber in the carrier, a stud pipe leading from the vacuum chamber in the mold, and a flexible hose having its opposite ends connected with said stud pipes.

3. In combination, a mold comprising two mating sections having depressions in their mating faces constituting a casting cavity and a vacuum chamber adjacent the cavity and connected thereto by a narrow passage, a vacuum pipe opening through one of said mold sections into the vacuum chamber, and a removable baffle plate in the chamber in front of the vacuum pipe and preventing direct entrance to the pipe of any metal passing through said passage into said chamber.

In testimony whereof, I have hereunto signed my name to this specification.

AUGUST KADOW.
